UNITED STATES PATENT OFFICE.

WALTHER FELD, OF HÖNNINGEN-ON-THE-RHINE, GERMANY, ASSIGNOR TO
THE AMERICAN SUGAR REFINING COMPANY, OF NEW YORK, N. Y.

PROCESS OF EXTRACTING SUGAR.

SPECIFICATION forming part of Letters Patent No. 592,517, dated October 26, 1897.

Application filed April 6, 1896. Serial No. 586,435. (No specimens.)

To all whom it may concern:

Be it known that I, WALTHER FELD, a subject of the German Emperor, residing at Hönningen-on-the-Rhine, Rhine Province, German Empire, have invented certain new and useful Improvements in Processes of Extracting Sugar from Molasses and other Saccharine Liquors by the Use of Barium Hydroxysulfid, of which the following is a specification.

It has heretofore been proposed to extract sugar from molasses or other sacchariferous liquors or juices by the use of barium compounds obtained from barium sulfid, (BaS.) The barium sulfid is obtained by the reduction of commercial heavy spar or barium sulfate with coal. It is the fact that when barium sulfid is leached systematically with hot water it gives a solution of barium hydroxysulfid, (BaS + H₂O = BaSHOH,) a substance which is very soluble in hot water, but will crystallize easily from the solution if cooled down to ordinary atmospheric temperature. The authorities have not hitherto accepted this fact, but for the purposes of the present case the matter is not important, because any chemist may theoretically explain the chemical reactions differently, and can, as hereinafter illustrated, easily substitute other formulas for those herein given. In any event the practical result will be the same.

In the process of extracting sugar from molasses as heretofore practiced a solution supposedly of barium sulfid, but actually containing about thirty-five percent. to forty percent. of barium hydroxysulfid and having a temperature of about 145° Fahrenheit, is thoroughly mixed with molasses or other sacchariferous liquor in such proportions that the mixture will contain for each one hundred parts of sugar about one hundred and fifteen parts of barium hydroxysulfid. Theoretically this is about five per cent. more barium hydroxysulfid than is necessary; but it is advisable to use a small excess, and if the molasses contains glucose or invert sugar a proportionally larger amount must be added—thus for one part of glucose about one part of barium hydroxysulfid. This excess reacts upon the glucose and transforms it into barium compounds. By the reaction of the sugar the barium hydroxysulfid is split into barium oxid, which, by combining with the sugar, forms insoluble barium saccharate, and into

water and barium hydrosulfid, which remains dissolved in the waste lye, according to the formula:

This reaction takes place at all temperatures; but in order to accelerate it and have a complete precipitation of the saccharate it is usual to heat the mixture above 140° Fahrenheit. By filtration through filter-presses and washing in the usual manner with pure water or a solution of barium saccharate containing about one and one-half per cent. of sugar the barium saccharate is separated from the waste lye, which contains, besides the impurities originally present in the molasses, the whole quantity of barium hydrosulfid formed by the process, the excess of barium hydroxysulfid used, and in lesser quantity various barium salts formed by the reaction of the barium hydroxysulfid upon the glucose and other impurities of the molasses.

The present invention consists in the hereinafter-described method of extracting sugar from molasses or other sacchariferous liquors by the use of barium compounds in such manner as to effect the economical recovery of the barium and sulfur employed. To this end the waste lye produced as heretofore set forth is saturated with carbonic acid, and the barium compounds therein being thereby decomposed all the sulfur from them is transformed into gaseous hydrogen sulfid, while the insoluble barium carbonate remains suspended in the solution. The barium carbonate is separated from the waste lye by settling or filtration. The latter is commonly effected by the use of the ordinary filter-presses. The gaseous hydrogen sulfid is conducted to a gasometer, from which it is transferred to a furnace-chamber, wherein it is burned in the usual way with air in order to obtain the sulfurous acid which it is thus made to yield and which is available in the subsequent operations for recovering the barium employed.

The object of the subsequent steps of the process is to transform into barium sulfite the various barium compounds which have been produced in the earlier stages of the process. To this end the barium carbonate gained by saturating the waste lye with carbonic acid is mixed with water and treated either with sufficient sulfuric acid to trans-

- form the barium carbonate or other barium compounds present in it into barium sulfate, or it is treated with sufficient sulfurous acid to transform the barium carbonate or other 5 barium compounds present in it into barium sulfite, the latter expedient being preferable, because of the supply of sulfurous acid yielded by the burning of the hydrogen sulfid, as described.
- 10 The barium saccharate which has been separated by filtration from the waste lye is then mixed with water or sugar liquors, and the mixture may then be treated with sulfuric acid or with sulfurous acid, whereby the barium saccharate will be decomposed into an 15 aqueous solution of sugar and a barium sulfate or a barium sulfite, according to the acid employed. It is, however, preferable to treat the mixture of barium saccharate and water 20 with a sufficient quantity of carbonic acid to decompose it into an aqueous solution of sugar and barium carbonate and to then separate the barium carbonate from the sugar 25 solution by filtration, after which the barium carbonate may either be mixed with water for subsequent treatment either with sulfuric acid or sulfurous acid for the purpose of transforming it into either a barium sulfate or a barium sulfite, as before described.
- 30 The resulting barium sulfate or barium sulfite, as the case may be, having been separated from the liquor in which it is contained by filtration, which is commonly effected by the use of the ordinary filter-presses, is then 35 mixed with coal and heated in a reverberatory furnace in the ordinary manner and thereby transformed into barium sulfid, which is susceptible of being again used in the described manner to extract the sugar from an 40 other quantity of molasses or other sacchariferous liquor.
- The novelty in this process resides, first, in the preliminary saturation of the waste lye with carbonic acid, whereby all the sulfur 45 present is transformed into hydrogen sulfid, which by subsequent burning is made to yield sulfurous acid, and the subsequent treatment of the barium carbonate gained from the waste lye with sulfuric acid or with sulfurous acid,
- 50 whereby the barium compounds present in it are transformed into salts—to wit, barium sulfate or barium sulfite, as the case may be—either of which after separation from the lye by filtration is by reduction with coal transformed into barium sulfid, and, secondly, in the preliminary treatment of the aqueous mixture of barium saccharate with carbonic acid and the subsequent treatment of the resulting barium carbonate with sulfuric acid 55 or sulfurous acid, whereby there is obtained a barium salt—to wit, barium sulfate or barium sulfite—either of which is susceptible of being reduced to barium sulfid by burning with coal. After the barium saccharate is 60 decomposed the resulting sugar solution is boiled down and the sugar crystallized out of it in the ordinary manner.

What is claimed as the invention is—

1. In the processes of extracting sugar from molasses or other sacchariferous liquors by the use of barium compounds, the method of recovering from the waste lye the sulfur introduced in combination with barium, which consists in saturating the waste lye with carbonic acid, collecting the thereby-developed 75 gaseous hydrogen sulfid and burning the same to sulfurous acid.

2. In processes of extracting sugar from molasses or other sacchariferous liquors by the use of barium compounds, the method of 80 recovering the barium from the waste lye, which consists in first saturating the waste lye with carbonic acid and thereby forming barium carbonate; secondly, introducing a sulfur acid, thereby transforming the barium 85 carbonate into a sulfur salt of barium; thirdly, separating the barium salt from the waste lye by filter-presses, and, finally, reducing it in a reverberatory furnace to barium sulfid, substantially as described. 90

3. In processes of extracting sugar from molasses or other sacchariferous liquors by the use of barium compounds whereby barium saccharate is formed, the method of recovering the barium, which consists in first mixing the barium saccharate with water; secondly, saturating the mixture with carbonic acid, and thereby forming barium carbonate; thirdly, separating the barium carbonate from the sugar solution; fourthly, mixing the 95 barium carbonate with water; fifthly, introducing a sulfur acid and thereby transforming the barium carbonate into a sulfur salt of barium; sixthly, separating the resulting barium salt from the water, and finally, reducing it in a reverberatory furnace to barium sulfid, substantially as described. 100 105 110 115 120 125

4. The process of extracting sugar from molasses or other sacchariferous liquor by the use of barium compounds, as herein described, whereby the constituents of the compounds employed are recovered in suitable form for repeated use, which consists in treating a saccharine liquor with barium hydroxysulfid, thus forming barium saccharate; separating the barium saccharate from the waste lye; treating the waste lye and the barium saccharate separately with carbonic acid; separating the pure-sugar solution from the barium carbonate; burning the hydrogen sulfid obtained from the waste lye to sulfurous acid; treating the barium carbonate obtained from the saccharate and the barium carbonate present in the waste lye, with a sulfur acid and thereby forming a sulfur salt of barium, 125 finally, reducing the resulting barium salt to barium sulfid, substantially as set forth.

In testimony whereof I have affixed my signature in presence of two witnesses.

WALTHER FELD.
